Primary Examiner — Ian Simmons*Assistant Examiner* — Khawaja Anwar(74) *Attorney, Agent, or Firm* — Smyrski Law group, A P.C.**CLAIM**

The ornamental design for an electronic device rotation attachment, as shown and described.

DESCRIPTION

FIG. 1 is a perspective view of the electronic device rotation attachment showing my new design;

FIG. 2 is a front view thereof;

FIG. 3 is a rear view thereof;

FIG. 4 is a right side elevation view thereof;

FIG. 5 is a left side elevation view thereof;

FIG. 6 is a top view thereof; and,

FIG. 7 is a bottom view thereof.

The broken lines shown in FIG. 1 represent unclaimed environment and form no part of the claimed design.

1 Claim, 3 Drawing Sheets(56)
